UNITED STATES PATENT OFFICE

101,277

DESIGN FOR A RUBBER BOOT FOR FEMALES

Raoul Giorda Issaly, Grenoble, France

Application May 14, 1936, Serial No. 62,624
In France April 8, 1936

Term of patent 7 years

To all whom it may concern:

Be it known that I, Raoul Giorda Issaly, a citizen of France, residing at Grenoble, Department of Isére, have invented a new, original, and ornamental Design for a Rubber Boot for Females, of which the following is a specification, reference being had to the accompanying drawing, forming a part thereof.

Fig. 1 is a side view of a rubber boot for females showing my design.

Fig. 2 is a rear view of the same.

I claim:

The ornamental design for a rubber boot for females as shown.

RAOUL GIORDA ISSALY.
